UNITED STATES PATENT OFFICE

HUGH M. KENNEDY, OF MONTREAL, QUEBEC, CANADA, ASSIGNOR TO THE ROBERT MITCHELL COMPANY LIMITED, OF MONTREAL, CANADA

MAIL CHUTE

Application filed March 17, 1928. Serial No. 262,449.

This invention relates to new and useful improvements in mail chutes for conveying mail from the upper floors of a building to a mail receptacle below, and the 5 main object of the invention is to provide a mail chute which will allow quick and easy access to the interior of the chute for cleaning or clearing same of any mailing matter which should become lodged in any part of 10 the chute other than the receptacle.

According to my invention I provide a chute of channel cross section which is set into the wall of a building. The chute has inwardly projecting flanges or guides adapted to position removable panels which form the front of the chute. The panels are held in position by means of straps. These straps are movable in the horizontal direction and can be swung clear of the panels to 20 allow easy removal of same.

In the drawings which illustrate my improved chute:—

Figure 1 is a front elevation of part of my improved type of chute.

Figure 2 is a part sectional side elevation of the chute taken on the line 2—2 Figure 1.

Figure 3 is a part front elevation of one type of locking strap for the panels.

Figure 4 is a sectional side elevation of 30 the strap shown in Figure 3.

Figure 5 is a sectional plan of the chute showing a modified type of locking strap.

Figure 6 is a front elevation of the modified type of connection between the locking 35 strap and the junction bar as disclosed in Figure 5.

Figure 7 is a sectional end elevation of the strap shown in Figure 5 taken on the line 7—7.

Figure 8 is a perspective view showing the 40 panel locking bar pivotally connected to the junction, as shown in Figure 4.

Figure 9 is a perspective view of the connection shown in Figure 8, with parts broken away to clearly show the construction.

Figure 10 is a perspective view of the junction and panel locking bars shown in Figures 5 to 7, parts being broken away to show the lug secured to the panel locking bar.

Referring more particularly to the drawings, 11 designates a chute which is made of channel cross section having inwardly extending flanges or guides 12, near the front edge thereof. The chute fits into a recess 13 formed in the wall 14. Removably fitting into the chute are the panels 15 which are preferably provided with a transparent central section fitting into a metallic frame. Surrounding three sides of the chute are 60 the straps 16 for connecting the various sections of the chute. The cross bars 17 which support the lower edge 18 of the uppermost panel are secured by any suitable means to the junction straps 16. A panel locking bar 65 18^a which fits over the lowermost edge of the upper panel and the upper edge of the lower panel is provided and is locked to the bar by any suitable lock designated 19. The lock is not shown in detail as any of the 70 well-known types may be used for this purpose. The bar 18^a fits over the front and the sides of the chute or the junction bars. In the preferred form shown in Figures 3 and 4, the legs 20 of the bar 18^a are provided with elongated lugs 21, the ends of 75 which are rounded for the purpose herein-after described. These lugs fit into slots 23 formed in the legs 22 of the junction bar. Part of the said slots is substantially equal 80 in width to the width of the lugs, so that when the locking bar is in the closed position, the locking bar is prevented from vertical movement but can be moved horizontally. The lugs, when the locking bar is pulled 85 outwardly as shown in dotted lines, fit into a circular recess 24 equal in diameter to the length of the lugs 21, so that the bar may be swung upwardly or downwardly to clear the adjacent edges of the panels and allow 90 same to be pulled clear of the panel locking bars. When the locking is pulled further, the lug fits into the upwardly curved portion 23^a of the slot 23 and holds the locking 95 clear of the upper edge of the lower panel, in proximity thereto.

In the modified form shown in Figures 5 to 7 inclusive, the lugs 21^a are formed in the junction straps and the slots 23^a are formed in the legs of the locking bar. The 100

slots are similar in shape to the slots 23 and, when the locking bar is pulled out, the circular recess 24^a is pulled outwardly towards the lugs and allows the said locking bar 5 to pivot to clear the panels, so that they may be quickly removed.

The operation of the device is very simple. The locking bars, when unlocked, can be pulled outwardly and then swung clear to 10 allow easy removal of the panels for cleaning or clearing the chute of any mail which may be clogging up the chute, and when the curved slot is used, the locking bar may be pulled outwardly until the lug engages with 15 the curved slot to hold the locking bar clear of the lower panel to allow easy removal of same. The fittings are very inexpensive to manufacture and can be easily and quickly fitted into position.

20 Having thus described my invention, what I claim is:

1. In a mail chute of channel cross section, junction straps surrounding three sides of the chute, cross bars supporting panels 25 removably mounted in the chute, and locking bars connected to the junction straps by lugs slidably and rotatably mounted in slots to allow the straps to be pulled from panel engaging position and swung clear 30 of the adjacent edges of the panels.

2. In a mail chute of channel cross section, junction straps for the chute, panels 35 slidably fitted into the chute and resting on cross bars secured to the junction straps, locking bars adapted to engage with the adjacent edges of the panels and to cover the cross bars and the legs of the junction bars, lugs formed in the locking bars and engaging with slots formed in the junction bars, 40 said slots being shaped to hold the bars in engagement with the panels and to allow the locking bars to be pulled forward and swung clear of the edge of the panel.

3. In a mail chute of channel cross section, junction straps for the chute, panels 45 fitting against guides formed in the chute and resting on cross bars secured to the junction straps, locking bars adapted to cover the adjacent edges of the panel and 50 also to cover the cross bar and the side legs of the junction bar, said locking bars having elongated lugs riding in slots in the junction bars, said slots having a circular recess to allow the lugs to rotate therein 55 when the locking bars are pulled outwardly to clear the panel edges.

4. The combination of a mail chute channel shaped in cross section, junction straps extending around the rear and sides of the 60 chute, cross bars secured to the sides of the junction straps to extend across the front of the chute, panels slidably fitted in the chute and resting on said cross bars, locking bars adapted to engage adjoining edges of 65 adjacent panels and to cover the cross bars,

said locking bars being provided with side legs telescoping the sides of the junction straps, horizontally disposed elongated lugs carried by the sides of the junction straps and fitting elongated slots formed in the 70 legs of the locking bars, said slots being provided intermediate their length with enlarged portions and being sufficiently narrow at opposite sides of said enlarged portions to prevent turning of the lugs except 75 when the latter are disposed in the enlarged portions of the slots by outward movement of the locking bars and means for securing the locking bars to said cross bars.

In witness whereof, I have hereunto set 80 my hand.

HUGH M. KENNEDY.
